UNITED STATES PATENT OFFICE.

FREDERICK E. KOHLER, OF CANTON, OHIO.

DESIGN FOR A LAWN-RAKE HEAD.

SPECIFICATION forming part of Design No. 28,813, dated June 7, 1898.

Application filed October 31, 1896. Serial No. 610,766. Term of patent 7 years.

To all whom it may concern:

Be it known that I, FREDERICK E. KOHLER, a citizen of the United States of America, residing at Canton, in the county of Stark, in the State of Ohio, have invented and produced a new and original Design for Lawn-Rake Heads, of which the following is a specification, reference being had to the annexed drawing, forming a part hereof, and wherefore in the figure is a perspective view of a lawn-rake head, showing my new design.

As shown in the drawing, the leading or material feature of my design consists of a rake-head bar 1 of the requisite length, produced from a single plate or strip of metal formed with parallel flanges 2 3, through which the U-shaped rake-teeth 4 are projected and curved vertically transversely to the rake-head, as shown in the drawing. Longitudinally on the vertical face of the rake-head bar and extending the length thereof are formed or produced upper and lower ribs or heavy heads 5 6, between which

is a pronounced circular channel or groove 7. It will be perceived that these alining or parallel ribs, in conjunction with the depression or groove between them, produce a unique and pleasing appearance to the eye and readily distinguish my design from the plain surfaces appearing in rake-heads of the construction heretofore employed.

On the front of the rake-head is formed the handle-socket, as shown in the drawing.

Having thus described my invention, what I claim, and desire to secure by Letters Patent, is—

The design for a lawn-rake head, as herein shown and described.

In testimony whereof I sign this specification, in the presence of two witnesses, this 20th day of October, 1896.

FREDERICK E. KOHLER.
